[57] CLAIM

The ornamental design for an electric steam iron, as shown and described.

DESCRIPTION

FIG. 1 is a perspective view, taken from the front, right side, and top, illustrating our new design of an electric steam iron; FIG. 2 is a left side elevation view thereof; FIG. 3 is a right side elevation view thereof; FIG. 4 is a front elevation view thereof; FIG. 5 is a rear elevation view thereof; and, FIG. 6 is a top plan view thereof.

The broken lines showing the electrical cord is for illustrative purposes only and forms no part of the claimed design.
